UNITED STATES PATENT OFFICE.

WILLIAM L. MILLER, OF PITTSBURG, PENNSYLVANIA.

AUTOMATIC WATER-HEATER.

SPECIFICATION forming part of Letters Patent No. 606,068, dated June 21, 1898.

Application filed October 1, 1897. Serial No. 653,670. (No model.)

To all whom it may concern:

Be it known that I, WILLIAM L. MILLER, a citizen of the United States, residing at Pittsburgh, in the county of Allegheny and State of

5 Pennsylvania, have invented or discovered a certain new and useful Improvement in Automatic Water-Heaters, of which improvement the following is a specification.

The object of my invention is to provide an 10 improvement in automatic water-heaters; and to this end it consists in a new and improved water-heater, in new and improved means for controlling and regulating the supply of heat, and in certain combinations and features of 15 construction, all as hereinafter fully set forth.

My invention provides a new and improved 20 automatic water-heater for supplying hot water to one or more faucets in which the supply of heat to a water-receptacle in which the 25 water is to be heated is controlled by variations in the pressure of the water in the outlet pipe or passage, caused by opening or closing, or partly opening or closing, one or more valves or faucets through which the hot wa-

25 ter is drawn off for use.

My improved heater is efficient in operation, is adapted to furnish a supply of hot water practically instantaneously, is simple and inexpensive in construction, and dispenses with 30 objectionable features heretofore employed in heaters of this class—such, for example, as a water-controlling valve whose movement depends on or controls the velocity of flow of the water through the heater, and which is usually 35 connected with the gas-controlling valve for regulating the supply of heat. In such constructions as have been employed heretofore the employment of the water-valve involves either the employment of two separate valve 40 devices and two separate casings with stuffing-boxes and objectionable outside connections, or else the construction is not such as to prevent the admission of water to the gas pipe or passages and to form at the same time 45 a sensitive or easily-operated valve device for controlling the supply of heat.

In the accompanying drawings, which illustrate an application of my invention, Figure 1 is a central vertical section through an automatic water-heater constructed in accordance

with my invention. Fig. 2 is a plan view of the regulating device, and Fig. 3 is a central section through a modification of my improvement.

As shown in Fig. 1 of the drawings, a heating-coil 1 is inclosed in a casing 2, which is lined with non-conducting material 3 and supported on the standards 4 or otherwise. One end 5 of the coil and one end of a water-supply pipe 7 from the city main or other source 55 of supply are connected with the regulator and are at all times in open communication with one another through the passage 8, the capacity or cross-sectional area of which should be about the same as that of the coil 1. 60 The width of the port 8 in a direction perpendicular to the plane of the drawings should therefore be somewhat greater than the width, as shown in Fig. 1 of the drawings. The pipe 7 may be connected to the upper portion 6 of 70 the regulator, if preferred, or the coil 1 and the pipe 7 from the main may be directly connected with one another outside of the regulator.

The regulator, as shown in Figs. 1 and 2, 75 comprises an upper portion 6 and a lower portion 9, between which is clamped a movable abutment or diaphragm 10, the under side of which is at all times exposed to the pressure in the pipe 7 and in the end portion 5 of the 80 coil 1, the water being admitted to the under side of the diaphragm through the passage 11. A smaller abutment or diaphragm 12 is held in place by a cap 13, which is secured to the lower portion of the regulator, and the two 85 diaphragms are connected by means of a stem 14, to the lower end of which is secured a valve 15 for controlling the port 16, through which gas is supplied to the burner. The seat of the valve 15 is formed on the inner 90 side of the cap 13, and the gas-supply pipe 17 is connected to a screw-threaded passage formed in the cap. The smaller diaphragm 12 separates the water-chamber between the two diaphragms from the valve-chamber and 95 prevents the passage of water into the gas pipes or passages.

Passages 18 and 19 lead from the valve-chamber to the jet 20, which delivers the gas into the perforated tube 26. The tube 26 100

forms a mixing-chamber for the air and gas, the air being admitted thereto through the lower open end, and the gas is burned outside of the tube 26 as it issues from the small holes 21. A small pipe 23 extends upward from the pipe 17, and at its upper end is provided with a burner which is always lighted and which ignites the gas as it escapes from the main burner 26.

10 The chamber above the diaphragm 10 communicates with the outlet end of the coil 1 or, as shown in the drawings, with a pipe 22, leading to the valve or valves controlling the discharge of water from the heater. For this purpose a pipe 25 is shown leading from the chamber above the diaphragm to the outlet-pipe 22, but, if preferred, the outlet-pipe or the outlet end of the coil may be directly connected to the upper portion of the regulator, 15 and the connecting-passage between the pipe or coil and the chamber above the diaphragm may be formed in the casting 6.

It will be seen that in my improvement there is a continuously-open free passage from the 25 inlet or supply pipe 7 through the coil to the outlet or delivery pipe 22 and that the flow of water through the heater is therefore unobstructed except by the outlet valve or valves, through which the hot water is drawn 30 when needed.

When the heater is not in use, the gas-valve is held closed by the water-pressure above the diaphragm 10 and by the pressure of the spring 24. When no water is being drawn, 35 the effective pressure of the water above the diaphragm will always be greater than the effective pressure of the water below the diaphragm, because the pressure on the small diaphragm is downward and counterbalances 40 a portion of the upward pressure.

The coil 1 is preferably made of thin copper or other piping of good conducting material, and on account of the great number of coils presents a large heating-surface.

45 On the opening of one or more of the faucets or valves through which the hot water is drawn off the pressure on the upper side of the diaphragm will be reduced and the pressure below the diaphragm will move the diaphragm upward and unseat the valve 15. Gas will then flow to the burner, where it will be ignited by the flame at the upper end of the small pipe 23, and the coil and the water passing through it will be quickly heated.

50 The chamber above the diaphragm being directly connected with the outlet portion of the heater any reduction of pressure in the outlet, such as may be caused by opening one or more faucets, will be immediately effective 55 to permit the upward movement of the diaphragm by the pressure from the main which acts on the under side of the diaphragm and which is admitted thereto through the passage 11.

60 The cross-sectional area of the pipe 7 relative to the cross-sectional area of the coil 1

and also the capacity of the passage 11 should be such that a steady pressure, substantially the same as the pressure in the main, may be maintained below the diaphragm 10.

70 The water supplied to the heater through the pipe 7 will fill the chamber below the diaphragm 10 and flow through the passage 8 and coil 1 to the outlet-pipe 22, and the pressure in the chamber above the diaphragm 10 75 and in the small pipe 25 will be the same as in the outlet-pipe. There need not be any flow or circulation of water through the chamber below the diaphragm 10 or through the chamber above the diaphragm, and the only 80 thing necessary to operate the gas-controlling valve is a variation in the outlet-pressure, and this variation need not produce any material variation in the pressure in the chamber below the diaphragm.

85 The operation of my improved heater is not dependent on the velocity of flow of the water to the heater or through the heater, but only on a variation of pressure such as might act later to vary the velocity of the water or 90 to impart velocity to or overcome the velocity of the water. A change in the pressure in the outlet-pipe and in the chamber above the diaphragm may be effected almost instantly, while to change the motion of the water or to 95 put it in motion through the coil, which forms a long and tortuous passage, would require a considerable interval of time.

When water is flowing through the coil, 100 there is a considerable difference in the pressure at the inlet and outlet ends of the coil and any variation at the outlet will be felt at or near the inlet end of the coil only after a considerable interval of time. In my improvement the operation of the valve is practically instantaneous and no interval of time 105 is necessary, such as that required to transmit a variation in pressure or velocity from one end of the coil to the other.

110 My improved heater is perfectly free from danger of explosion, as the pressure in the coil can never exceed the pressure in the main, because the coil is always in open communication with the water-main. In case, therefore, that the gas-controlling valve 15 should 115 fail to close when the faucet or faucets are shut off no amount of heating can cause an explosion.

120 In case of a break in the main or in the supply-pipe 7 the water will escape from the under side of the diaphragm and the valve 15 will close. If there is no pressure acting on the diaphragm, the valve will be closed by the action of the spring 24. The tension of the spring 24 need not be any greater than is 125 necessary to close the valve and to keep it closed when the diaphragm 10 is relieved of other pressure, so that the difference in the water-pressures above and below the diaphragm 10 which will be required to move the 130 diaphragm and open the valve need not be much greater than that due to the difference

in the effective areas of the opposite sides of the diaphragm 10.

In Fig. 3 of the drawings I have shown a heater embodying my invention in which the 5 heating-coil 1 is formed of a tube or pipe which is approximately elliptical in cross-section. The coil is made of thin copper or other good conducting material, the end portions 5^a and 5^b of which are circular in cross-section, and 10 the remainder of the coil, which forms the heating portion of the coil, is flattened by being passed between rolls or by any other preferred means. Preferably the piping of which the coil is made is at first circular in cross- 15 section and is afterward flattened out to any extent desired by a simple and inexpensive process. The object in giving the piping the particular form referred to is to increase the heating effect by increasing the heating-surface 20 relative to the quantity of water contained in the coil. This is accomplished by giving the flattened or elliptical shape to the pipe without increasing the length of the pipe. This particular form of piping is specially 25 adapted for employment in my improved heater, in which the pressure within the coil and pipes is limited to the pressure in the water-supply main, and the pressure will therefore never be great enough to change 30 the form of the cross-section of the pipe, as it might be in steam-boilers or in water-heaters in which it is possible to accumulate a greater pressure than the pressure in the main. Any 35 tendency to change of form of the cross-section is further counteracted in my improvement by the coiled form of the piping and the comparatively small diameter of the coils. In my improvement there can be no change of form of the cross-section of the pipe without 40 a change of form or straightening of the coils, and it would require an enormously high pressure, very much in excess of any pressure which can be obtained in the coil, to effect any such change in the form of the coil. The 45 material of which the pipe is made may be very thin, so as to permit rapid heating without any danger of rupturing the pipe on account of the limited pressure.

In Fig. 3 of the drawings the outlet-pipe 50 from the water-supply main is to be connected to the screw-threaded nozzle 27, which is integral with the upper portion 28 of the regulator, and the inlet end 5^a of the heating-coil is connected with the inlet-nozzle 27 by means 55 of a union 29, so that there is a full and free opening through the nozzle into and through the inlet end 5^a of the heating-coil. The outlet end 5^b of the heating-coil is similarly connected by means of a union 30 with the outlet-nozzle 31, which is screw-threaded to receive one end of the outlet-pipe which leads to the outlet valves or faucets, through which the hot water is drawn for use. The outlet-nozzle 31 is formed integral with the lower 60 portion 32 of the regulator. The upper and lower portions 28 and 32 of the regulator are

secured together by bolts 33, and between them is clamped a diaphragm 34, which divides the interior into two chambers 35 and 36. The upper chamber 35 is at all times in 70 open communication with the water-supply main and with the inlet end of the heating-coil through the passages 37 and 38, and the lower chamber 36 is at all times in open direct communication with the outlet-pipe through 75 the passage 39 and the opening in the nozzle 31.

A small diaphragm 40 is clamped in place by an annular plate 41, which is secured in place by small screws, and the two diaphragms 40 and 34 are connected together by a screw-threaded bolt and nuts or by any desired means which will cause them to move together. A gas-controlling valve 42, which is secured to the diaphragms and is adapted to be moved by them, is normally held closed by the unbalanced upward pressure of the water on the lower side of the diaphragm 34 and the pressure of the spring 43.

The gas-supply pipe is connected to the nozzle 45, formed integral with the upper side of 90 the regulator, and the gas is admitted to the valve-chamber through the passage 44. The gas-valve 42 controls the supply of gas to the jet 46, from which it passes into the burner 47.

The burner 47 is preferably circular in 95 shape and is provided with openings or perforations 48, through which the mixed air and gas pass from the interior of the burner and at which they are ignited. The upper portion of the interior of the burner curves 100 downwardly from its outer upper portion toward the center and toward the jet 46, and the lower portion of the burner is provided with a conical hood or short flaring pipe, which surrounds the jet 46 and into which air is admitted through openings 49.

Both the air and gas in flowing into the burner impinge on the sides 50 of the central tapered portion or deflector 51 and are then reverberated and mixed with a whirling action against the wall of the burner before passing out through the openings 48, where they are ignited.

A small pipe 52 is connected with the interior of the nozzle 45, and on the end of the 115 pipe 52 is a burner 53, which may be kept burning for the purpose of igniting the gas from the openings in the main burner 47. The supply of gas to the small burner 53 is controlled by a valve 54.

In the construction shown in Fig. 3 of the drawings a full and free open passage is shown from the connection with the main supply-pipe through the coil to the outlet connection for the purpose of preventing any obstruction of the flow from the main to the outlet-valves or faucets or backward to the main in case of a sufficient increase of pressure in the coil to overcome the pressure in the main.

When no hot water is being used—that is, 130 when the outlet-valve or faucet is closed—the pressure in both ends of the coil and in both

of the chambers 35 and 36 will be the same and the gas-valve 42 will be held closed; but as soon as an outlet-valve is opened the pressure in the chamber 36 will be immediately reduced, the gas-valve 42 will open and permit the gas to flow to the burner, and as the mixed air and gas escape from the openings 48 the mixture will be ignited by the flame from the burner 53 and the water in the coil 10 will be heated.

In Fig. 3 of the drawings the outer casing 2, within which the heating-coil is inclosed, is secured at its lower end to a casting 55, to which are bolted the supports 56. A screw-threaded nipple 54, which extends downward from the gas-jet 46 of the burner, passes through the casting 55 and screws into the upward extension 59 of the regulator, thereby clamping the regulator to the casting 55. A bolt 57 passes through the top plate or cover 58 of the casing and at its lower end screws into the burner 47, thereby securing the regulator, the casting 55, and the burner and the top of the casing firmly together and forming 25 a rigid support for the ends of the coil.

In Fig. 3 of the drawings the principal features of my improvement are clearly shown, and that construction may be regarded as a preferred form of my improvement; but my invention is not limited to all the details of construction shown in any of the drawings. An important feature of my invention is the free and unobstructed passage through the heater, by which the flow of water through 35 the heater is unaffected by and independent of any regulating-valve or other device except the outlet valve or valves through which hot water is drawn for use. Another important feature of my invention is the means for regulating the supply of heat by variation in the pressure of the water at or near the outlet of the heater, by which the opening and closing of the gas-supply valve may be quickly and certainly effected.

45 By means of the flattened or elliptical form given to the piping in the heating-coil the thickness of the body of water therein is so small that the heat can quickly pass to the center of the mass of water and the water 50 can be very quickly and uniformly heated throughout its whole mass without even a local circulation of the particles, such as is required in a coil of circular section before the central portion of the water therein can 55 be heated. The form of the mass of water in the heating-coil is that of a liquid ribbon, the thickness of which may be so slight that the heating of the whole mass may be practically instantaneous.

60 The burner and mixing device shown in Fig. 3 is preferably circular in form in its upper part, and the whole device may be made of one integral casting. It will be seen that when air and gas are being admitted to the 65 burner the gas will strike first against the de-

flecting-surface 50 of the downwardly-projecting part 51 and will be deflected outwardly therefrom in all directions, so that it will with a whirling action mingle with the entering air in the annular passage 60 and in 70 the chamber 61.

I claim as my invention and desire to secure by Letters Patent—

1. In an automatic water-heater, the combination, with a water-receptacle, having inlet and outlet passages communicating therewith, of a heat-supplying device, a heat-regulator, and direct connections with opposite sides of the regulator, outside of the water-receptacle, from the inlet and outlet passages 80 to the heat-regulator whereby the supply of heat may be controlled by a difference in the inlet and outlet pressures of the water, substantially as set forth.

2. In an automatic water-heater, the combination, with a water-receptacle, of inlet and outlet passages communicating with the receptacle, means for heating the water-receptacle, a heat-regulator outside of the direct flow of water, comprising a valve for controlling the supply of heat and a movable abutment for actuating the valve, a direct connection from the outlet-passage to one side of the abutment and a connection from the inlet-passage to the opposite side of the abutment, whereby the abutment may be operated by variations of pressure in the outlet from the water-receptacle, substantially as set forth.

3. In an automatic water-heater, the combination, with a heating-coil, of a heat-supply, a heat-regulator, outside of the direct flow of water, comprising a valve for controlling the supply of heat to the coil and a movable abutment for operating the valve, 105 which is exposed to the pressure of the water at or near the inlet and outlet portions of the coil, substantially as set forth.

4. In an automatic water-heater, the combination, with a water-receptacle provided 110 with an inlet and an outlet, of a heat-supply, a heat-regulator outside of the direct flow of water and subjected on one side to the pressure of water flowing to the water-receptacle and on the other side to the pressure of water flowing from the receptacle, substantially 115 as set forth.

5. In an automatic water-heater, the combination, with a water-receptacle having inlet and outlet passages, of a water-supply pipe, 120 means for heating the water-receptacle, a heat-controlling device outside of the water-supply pipe and the direct flow of water, and connected with the inlet and outlet passages of the water-receptacle whereby variations of 125 pressure between the inlet and outlet passages will operate the controlling device, substantially as set forth.

6. In an automatic water-heater, the combination, with a water-receptacle having in- 130

let and outlet passages, of an unobstructed water-passage from the water-main to the delivery-valve, or faucet, a heat-supplying device, a heat-regulating device for controlling the supply of heat to the coil located outside of the water-passage and having connections to the inlet and outlet of the coil, and adapted to be operated by variations of pressure in the

outlet-passage of the water-receptacle, substantially as set forth.

In testimony whereof I have hereunto set my hand.

WILLIAM L. MILLER.
